FINGERPRINTING APPARATUS

Joseph Seres, Jr., Cleveland, Ohio

Application February 25, 1936, Serial No. 65,692

18 Claims. (Cl. 91—54)

In the art of making fingerprints for Bertillon cards or other identification purposes, it has been the practice heretofore to apply the fingerprint ink to the finger tips of a person by placing the 5 finger tips upon a surface or base to which a thin layer of ink has been applied and evenly distributed by means of a rubber roller or the like, and rotating the finger with respect to the inked surface so as to apply the ink to the sides and 10 bottom of the finger tip. This method of inking the finger tips is very unsatisfactory because the slightest movement of the finger with respect to the inked surface will cause the entrance of ink into the depressions between the lines of 15 the finger to be reproduced, and the prints obtained from such improperly inked finger will be smudgy and will not suffice for purposes of classification or identification. It is therefore quite often necessary to repeat the inking process 20 several times before clear prints are obtained.

Another disadvantage of the present manner of inking the finger tips is that the same have to be rotated with respect to the inked surface so as to also apply the ink to the sides of the 25 finger tips, which is necessary to produce proper prints for identification purposes. Such turning of the fingers is very inconvenient for a person whose fingerprints are taken, and the possibility of moving the finger with respect to the inked 30 surface during such turning operation is considerably increased, so that ink may be forced into the depressions between the lines of the finger as above mentioned, and the results obtained in reproducing the lines upon a Bertillon 35 card or the like will not be sufficiently clear for the above purpose.

The present invention has been devised to overcome the above difficulties and provides a mechanism for the inking of finger tips preparatory to the making of impressions therefrom, wherein the likelihood of movement of the finger with respect to the ink carrying surface is substantially eliminated.

The present invention provides a finger inking apparatus comprising a flexible member upon which fingerprint ink is evenly applied so that, when the finger tip is placed upon the flexible member and the same is depressed, the bottom as well as the sides of the finger tip will be properly inked without the necessity of turning the finger with respect to the inking surface.

Other and further objects of the invention will become apparent from the following description and drawing, in which—

55 Figure 1 is a front view of the finger inking

device of the present invention, the front cover plate being removed for purposes of showing the mechanism of the apparatus more clearly.

Figure 2 is a top view of the illustration shown in Figure 1.

Figure 3 is a sectional view taken on line 3—3 of Figure 2.

Figure 4 is a partial view of the inking apparatus, similar to Figure 1, the flexible member, however, being shown in depressed position.

Figure 5 is a perspective view of the finger inking apparatus of the present invention.

Figures 6 and 7 are views illustrating an ink supply mechanism which may be advantageously used in connection with the present invention.

Figure 8 shows a modified structure of ink supply mechanism.

Referring now to the drawing, and particularly to Figures 1 and 5, 1 indicates a housing or casing within which a V-shaped frame member 2 is positioned and secured to the bottom 3 of the housing by the use of any convenient fastening means 4. Adjacent the rear wall 5 of the housing 1 is a supporting plate 6 which is secured to the said housing by means of screws 7. Interposed between the V-shaped frame 2 and the supporting plate 6 is a plurality of rubber or composition rollers 8, 9, and 12. The rollers 8, 9 and 12 are mounted upon shafts 13 which are supported within holes or bearing portions 14 of the V-shaped member 2 and plate 6. Adjacent the rollers 8, 9 and 12 are rollers 15, 16 and 17, movably arranged within the V-shaped frame 2 and plate 6 and urged toward the rollers 8, 9 and 12 by means of coil springs 18, 19 and 20, respectively. The shafts 21 of the rollers 15, 16, and 17 are positioned within slots 22, 23 and 24, respectively, in the V-shaped frame and plate 6 so as to maintain the same in proper position with respect to their supporting members. Arranged between rollers 8 and 15, 9 and 16, and 12 and 17 is an endless flexible member 25, and it will be seen that by the provision of the coil springs 18, 19, and 20 the said flexible member 25 is maintained in frictional engagement with the rubber or composition rollers.

The shaft 26 of roller 12 extends rearwardly of the plate 6 and is provided with a beveled gear 27 keyed to the same and in operative engagement with a corresponding beveled gear 28 keyed to a turning or crank shaft 29. Shaft 29 is rotatably mounted within the side wall 1a of the housing 1 and a bearing member 30, secured to the back wall 5 of the housing, is provided for 55

supporting the end of shaft 29 adjacent the bevelled gear 28.

The housing 1 is preferably provided with a front wall 31 provided with outwardly extending portions 32 for housing the end portions of the roller shafts extending forwardly of the V-shaped plate and springs 18, 19, and 20 so as to permit their free movement, as will be explained later on.

A cover member 33 is secured to the housing 1 and is hinged thereto in such a manner as to permit access to the flexible or ink carrying member 25, for purposes explained hereinafter.

From the above it will be seen that the flexible or ink carrying member 25 is held in frictional contact with the rollers of the inking apparatus of the present invention, and upon rotation of crank shaft 29 and roller 12, shifting of the endless flexible member 25 in the direction indicated by the arrow in Figure 1 will be accomplished.

20 In the operation of the device, fingerprint ink is applied to the roller 9; upon rotation of the crank shaft 29 the flexible member 25 is shifted in the direction shown by the arrow in Figure 1, and the fingerprint ink is evenly distributed over 25 the outer surface of this member. The roller 9 therefore functions as an ink applicator which spreads the ink thinly over the surface of the flexible member.

In inking the finger tips of a person whose 30 fingerprints are to be taken, finger 34 of such person is placed upon the flexible member 25, as clearly seen in Figure 5, whereupon the finger is pressed downwardly in the direction indicated by the arrow in this figure, to a position as shown 35 in Figure 4, and the rollers 15 and 16 are thereby forced downwardly and the flexible member 25 folds around the finger 34 and applies the ink to the bottom and sides of the same, whereupon the properly inked finger is then removed from the 40 device by raising the same upwardly, and impressions of the finger tip may now be taken in the usual manner.

The front plate 31 of the finger inking device is provided with a V-shaped cut-out portion 31a 45 which conforms to the configuration of the frame 2 so as to permit the downward movement of the finger as explained in regard to Figure 5. The impressions of the finger tips inked in the manner heretofore described may be taken with a device of a construction similar to that described herein. However, instead of the member 25, an 50 impression member, preferably made from paper or like impression material, may be arranged between the composition rollers. In such instance of course it would be necessary to have one apparatus for inking the finger tips and another apparatus with the impression reproducing member for the reproduction of the fingerprints.

It will be seen therefore that in this manner a 60 perfect inking of the finger tips may be obtained without smearing the ink into the impressions between the lines of the finger to be reproduced, and clear prints may therefore be made. The springs 18, 19, and 20 may be calibrated to the 65 exact pressure necessary for proper application of the ink without forcing the same into the ridges between the lines of the finger.

Figures 6 and 7 illustrate an arrangement for 70 applying ink to the ink applicator or roller 9 which consists of a container 35 having an extension 36 extending into the housing 1 and adjacent the roller 9 through a slot 37. The slot 37 extends substantially over the width of the side wall 1a and into the compartment 38 between the 75 rear wall 5 of the housing and plate 6. The ex-

tension 36 at its open end 37a is provided with a wick or sponge rubber member, the latter being arranged in such a manner as to contact with the roller 9. Guide and supporting members 39 are provided on the ink compartment 35 to maintain the same in proper position while permitting shifting of the latter in a horizontal direction. A cover plate 40 eliminates the entrance of dust or other foreign particles into the ink compartment.

When the member 35 is shifted in a horizontal 10 direction ink will be applied by the wick 39a to the roller 9 and the member 35 is then shifted to a position so that the extension 36 and wick 39a are within the compartment 38 and out of contact with roller 9. Upon rotation of the flexible member 25, ink will be applied from the roller 9 to the member 25 and will be evenly distributed thereon in the manner outlined above.

When the apparatus is out of use, the cover 20 33 is applied and entrance of dust to the ink carrying member is effectively prevented.

From the foregoing it will be seen that I have devised a novel inking apparatus which eliminates the disadvantageous features of present-day devices used for the purposes mentioned hereinbefore, and which permits inking the finger tips of a person preparatory to taking impressions therefrom, in a very efficient manner, and wherein the likelihood of smearing the ink into the ridges between the lines of the fingers 30 has been substantially eliminated.

Figure 8 shows a modified construction of ink supply mechanism as may be preferably used in connection with fingerprint ink of a paste-like consistency. The tubular portion 41 extends 35 through slot 37 of the casing into close proximity with roller 9, and is held in proper position with respect to the casing by washers 42 and 43 soldered or welded to the portion 41 in a manner clearly illustrated in Figure 8. The 40 member 41 is provided with a threaded portion 44 cooperating with a threaded portion 45 of the cup member 46. When the supply mechanism is filled with ink and the cup 46 is screwed upon member 41, the ink paste will be forced against 45 the roller 9. The ink supply mechanism may be shifted out of contact with roller 9 in the same manner as described in connection with Figures 6 and 7.

Having thus described my invention, what I 50 claim as new and desire to secure by Letters Patent of the United States, is—

1. In the art of fingerprinting, a finger inking device, comprising, in combination, a flexible member, spaced means for supporting the flexible member including ink applying means, said spaced means being movable downwardly and inwardly by the flexible member in inking operations, and instrumentalities for rotating said supporting means for shifting the flexible member to thereby transfer ink from said applying means to said flexible member.

2. In the art of fingerprinting, a finger inking device, comprising, in combination, a flexible member, resiliently mounted spaced supporting means for the flexible member, between which the flexible member is compressible, ink applying means associated with said flexible member, said flexible member being movable away from the inking means when the former is depressed and means for shifting the flexible member and rotating said supporting and applying means to thereby transfer ink from the latter to the flexible member.

3. In the art of fingerprinting, a finger ink-

ing device, comprising, in combination, a frame structure, a plurality of resiliently mounted and depressible rollers on said frame structure, said frame having means for guiding the rollers downwardly and inwardly, a plurality of rollers adjacent said resiliently mounted rollers, an endless flexible ink carrying member between said rollers and the resiliently mounted rollers and in frictional contact therewith, and means for 5 rotating one of said rollers for shifting said endless member and for rotating said resiliently mounted rollers and said rollers to thereby transfer ink from one of said rollers to the endless member.

15 4. In the art of fingerprinting, a finger inking apparatus, comprising, in combination, an endless flexible member, means for supporting the flexible member, ink applying means associated with said flexible member, instrumentalities for 20 rotating said supporting means for shifting the flexible member and for transferring ink from the ink applying means to the latter, resilient means associated with the supporting means for permitting depression of the supporting 25 means with the flexible member under the pressure of a finger placed thereupon and means for causing the supporting means to move diagonally inward during such depression, to fold the flexible member around the sides of said finger, to thereby apply ink to the latter.

30 5. In the art of fingerprinting, a finger inking apparatus, comprising, in combination, a housing, a V-shaped frame and a supporting plate within said housing, a plurality of rollers mounted between said plate and frame, a plurality of rollers vertically movable with respect to said frame and plate, a flexible ink carrying base supported between the first mentioned rollers and vertically movable rollers, resilient means for holding the flexible ink carrying member in frictional contact with the vertically movable rollers and said other rollers, and instrumentalities for shifting said base and for rotating the rollers for transferring ink from one of said first mentioned 35 rollers to said base, whereby upon depression of said base against the action of the resilient means, by a finger placed upon the same, said flexible ink carrying base is folded around the bottom and side portion of said finger for transferring 40 ink to the same.

45 6. In the art of fingerprinting, a finger inking device, comprising, in combination, a housing, a frame within said housing, a supporting plate within said housing, a plurality of stationary shafts mounted between said frame and plate, a roller on each of said shafts and rotatable thereon, a plurality of vertically movable shafts on said frame and plate, supporting rollers on said shafts, a flexible ink carrying member between said rollers and supporting rollers, means for urging said rollers, supporting rollers and flexible ink carrying member into frictional contact with respect to each other, and means for rotating one of said rollers to shift the flexible member 50 and for causing rotation of the other rollers and supporting rollers for distributing ink applied to one of said rollers over the surface of said base.

55 7. In the art of fingerprinting, a finger inking device, comprising, in combination, an endless flexible member, means for supporting the flexible member including ink applying means, instrumentalities for rotating said supporting means for shifting the flexible member to thereby transfer ink from said applying means to said flexible

member, and means longitudinally movable at will into and out of operative relation to said ink applying means for respectively supplying ink and discontinuing the supply of ink to the latter.

8. In the art of fingerprinting, a finger inking device, comprising, in combination, a housing, a frame within said housing, a supporting plate within said housing, a plurality of stationary shafts mounted between said frame and plate, a roller on each of said shafts and rotatable thereon, a plurality of vertically movable shafts on said frame and plate, supporting rollers on said shafts, a flexible ink carrying member between said rollers and supporting rollers, means for urging said rollers, supporting rollers and flexible ink carrying member into frictional contact with respect to each other, means for rotating one of said rollers to shift the flexible member and for causing rotation of the other rollers and supporting rollers for distributing ink applied to one of said rollers over the surface of said base, and means for supplying ink to one of said rollers.

9. In the art of fingerprinting, a finger inking apparatus, comprising, in combination, a housing, a cover plate hinged to said housing, a frame and a supporting plate within said housing and spaced with respect to each other, a plurality of rollers rotatably arranged between said frame and plate, an endless flexible ink carrying member in frictional engagement with said rollers and supported thereby, resilient means on some of said rollers for maintaining said frictional engagement and for holding said endless member taut, means for shifting said endless member and for rotating said rollers, and instrumentalities for supplying ink to one of said rollers for transmitting the same upon said endless member.

10. In the art of fingerprinting, apparatus for effecting operations incidental to fingerprinting, comprising, in combination, a flexible member against which a finger may be pressed to thereby cause a sort of folding action of the flexible member partly around the finger, spaced supporting means for said flexible member comprising parts movable downwardly and toward each other and permitting the yielding of the flexible member between said supporting means to enable the said contact and folding action of the flexible member respecting the finger, and instrumentalities for shifting the flexible member to bring fresh portions thereof into place between the supporting means for receiving the pressure actions of fingers in the use of the apparatus.

11. In the art of fingerprinting, apparatus as claimed in claim 10, combined with applicator means for applying ink to the flexible member, and parts coacting with the flexible member to distribute the ink thereover incident to the shifting movement thereof.

12. In the art of fingerprinting, apparatus as claimed in claim 10, wherein the flexible member is of endless form and passes around its supporting means to be shifted relatively to the latter as set forth.

13. In the art of fingerprinting, apparatus as claimed in claim 10, wherein the shifting instrumentalities comprise actuating devices for the supporting means of the flexible member.

14. In the art of fingerprinting, apparatus for effecting operations incidental to fingerprinting, comprising, in combination, a flexible member against which a finger may be pressed to thereby cause a sort of folding action of the flexible member partly around the finger, spaced supporting

- means for said flexible member downwardly movable in the direction of pressure of the finger and comprising parts permitting the yielding of the flexible member between said supporting means 5 to enable the said contact and folding action of the flexible member respecting the finger, guide means for causing the supporting means to move toward each other during the downward movement, instrumentalities for shifting the flexible member to bring fresh portions thereof into place between the supporting means for receiving the pressure actions of fingers in the use of the apparatus, applicator means for applying ink to the flexible member, and parts coating with the 10 flexible member to distribute the ink thereover incident to the shifting movement thereof, the said shifting instrumentalities comprising an actuating device for the supporting means of the flexible member to positively effect the shifting movement of the latter to bring fresh portions of the flexible member into place for depression by the finger and at the same time cause distribution of ink over the surface of said flexible member.
15. In finger printing apparatus of the class described, a flexible inking member, downwardly movable spaced supporting means over which said flexible member is passed and between which the inking member is compressible, and means for moving said supporting means toward each other in said downward movement when the flexible member is depressed to effect a wrapping of the flexible member about the sides of the finger in inking operations.
20. In finger printing apparatus of the class described, the combination of an endless flexible member, spaced supporting means for holding the ink applying reach of said member in operative position for depression, separate means for holding the return reach of the flexible member 25 spaced from the first reach to permit substantial depression of the said first reach, said spaced supporting means being yieldable downwardly with the depression of the flexible member, and means for moving the spaced supporting means 30 in such downward movement toward each other to effect a wrapping of the flexible member about the sides of the finger in finger inking operations.
35. In finger printing apparatus of the class

described, a flexible inking member, a pair of supporting rolls therefor between which the inking member is compressible, guide means constructed and arranged to permit downward and inward movement of the supporting rolls, and resilient means for sustaining the rolls in their uppermost position.

17. In finger printing apparatus of the class described, a flexible inking member, a frame, a plurality of spaced supporting rolls mounted in said frame in substantially triangular relation, said flexible member extending about said rolls, means yieldably holding certain of said rolls, said frame having guide means in which the last mentioned rolls are movably mounted for movement 15 downwardly and toward each other, inking means associated with the flexible member, and means for shifting the flexible member at will when the supporting rolls are in their uppermost position.

18. In finger printing apparatus of the class described, the combination of an endless flexible member, spaced supporting means for holding the ink applying reach of said member in operative position for depression, separate means for holding the return reach of the flexible member 25 spaced from the first reach to permit substantial depression of the said first reach, said spaced supporting means being yieldable downwardly with the depression of the flexible member, and means for moving the spaced supporting means 30 in such downward movement toward each other to effect a wrapping of the flexible member about the sides of the finger in finger inking operations.
